CONTAINER

Victor K. Le Comte, Forest Hills, N. Y., assignor
to Le Comte & Co., Inc., Brooklyn, N. Y., a corporation of New York

Application April 17, 1933, Serial No. 666,401

9 Claims. (Cl. 220—59)

This invention relates to containers, such as cans constructed of tin or similar material, and has for its principal object to provide a container adapted to be securely covered or sealed.

5 A related object is to enable a container or can to be covered in such a manner that the cover cannot be removed without considerable damage to the container or cover, or both.

Containers according to this invention are particularly suitable for enclosing or packing substances such as perishable foods which should not be permitted to be exposed at any time between the packing and the ultimate use.

Some foods, of which oysters are a typical example, are required by law to be packed in such a manner that no opening of the container is possible without ready detection of the unauthorized exposure of the enclosed product. The container, in accordance with this invention, is well suited to meet this requirement. Since parts of the container are automatically damaged by any opening of the same, it is impossible to again close or seal up the container after it is once opened; hence no such surreptitious opening is practicable.

In a preferred embodiment, the invention comprises a can member provided with a cover member adapted to be sprung into place at the top of the can. For this purpose, one of the members, preferably the can or container itself, is provided at its open end or edge with a resilient rim adapted to engage with a corresponding bead on the edge of the other member. The bead and the resilient rim, when in the normal condition, are of slightly different diameters, so that when the cover is applied to the container, the bead strains the resilient rim somewhat in moving past the rim to its proper closed position, whereupon, the rim reverts to its normal condition and bears against the bead so that the cover cannot be readily removed.

The invention will be more fully understood by reference to the attached drawing of which:

Fig. 1 is a view, partly in section, of a container 45 with a cover in the clamped position, according to this invention; and

Fig. 2 is an enlarged sectional view showing in greater detail the construction of the engaging portions of the container and cover.

50 Referring to the drawing, the container structure is a can 10 comprising a cylindrical portion 11 to which is attached a flat circular bottom 12. The cylindrical portion is composed of a rectangular piece of the can material, preferably tin, joined by a side seam 13 in a manner well known

to those skilled in the art of can manufacture. The circular bottom portion 12 is joined to the lower edge of the cylindrical portion by turning up a circular seam 14 in a manner also well understood in the art. For the purpose of obtaining increased strength and rigidity near the open edge of the container, a strengthening bead 15 is formed on the cylindrical wall somewhat below the edge. The edge of the cylindrical wall at the open end of the container is curled over to form 10 a resilient curled rim 16 within the circular edge at the top of the can.

The can cover 17 is formed by turning up the outer portion, or perimeter, of a flat circular piece of the material to form an outer circumference, 15 or edge 18, which will fit within the top of the container. There is formed on the outer circumference 18 a bead 19 and a flange 20, the flange being formed by curling over the edge of the metal, as shown. The flange is of greater diameter than 20 the bead; that is, about the diameter of the can. The diameter of the bead 19 is slightly greater than the normal inside diameter of the curled rim 16 within the top of the can, so that when the cover is forced into place, the bead presses against 25 the curled rim, thereby straining the latter to an increased diameter. This increased diameter of the rim may be due, in part, to a straining at the side seam 13. In the ultimate clamped position, 30 the bead assumes a position beyond the curled rim, as shown in the drawing, so that the rim reverts to its normal diameter, the lower edge of the rim resting on the upper surface of the bead. This upper surface of the bead is in the form 35 of a substantially horizontal engaging ledge, as shown, upon which the lower engaging edge of the rim tightly rests. The cover is thus firmly clamped in position by means of the curled rim 16, the upper edge of which contacts the flange 20 of 40 the cover and the lower edge of which is in contact with bead 19. Since the flange 20 is formed of a curled edge, it possesses natural resiliency, and the curled rim 16 is tightly and resiliently held 45 between the flange and the bead of the cover.

In order to remove the cover, it is necessary to 45 insert an instrument, such as a screwdriver, between the flange of the cover and the upper edge of the curled rim, or otherwise permanently deform the component parts. The bead 19 will then 50 be forced past the rim 16, thus tearing out and injuring the rim, because of the width of the bead, or the cover will be so deformed that it cannot again be clamped into place in the regular manner. An inspection of Fig. 2 clearly shows that 55 such permanent deformation of the parts must

necessarily occur because of the direction from which the engaging edge of the curled rim 16 contacts the engaging ledge of the bead 19. There is quite a wide angle between the ledge of bead 19 and the direction of engagement of the edge of rim 16.

It is not essential to the operation of this invention that the arrangement of the bead and rim be exactly as that shown in the drawing. For example, the resilient rim might be in the form of a curl on the outside, instead of the inside, of the open end of the can. Another arrangement might be that in which the resilient rim is formed on the cover and the bead upon the can. In this latter arrangement, it would be desirable to form the flange also upon the can.

I claim:

1. In combination, a container having a substantially continuous resilient rim formed by an open curl within the top of said container, said curl providing an engaging edge, and a cover adapted to be clamped on the open end of said container, said cover being provided with an outer circumferential bead having an engaging ledge, said rim and said bead being located with respect to each other so that in moving to the clamped position said bead moves past said rim and resiliently strains said rim in passing, and when in the clamped position said rim reverts to its normal unstrained condition, the outer diameter of said ledge being sufficiently greater than the normal diameter of said engaging edge, and said ledge making such an angle with respect to said edge, as to prevent said bead from moving out of said clamped position without permanently deforming said bead or said rim.

2. In combination, a container member and a cover member adapted to clamp on said container member, one of said members being provided with a bead having a substantially horizontal ledge and the other of said members being provided with a substantially continuous resilient rim formed by an open curl providing an engaging edge, the provision and arrangement being such that when said cover member is moved toward the clamped position, said bead engages and resiliently strains said rim, and when actually in the clamped position said bead assumes a position beyond said rim whereupon said rim reverts to its normal unstrained condition, said ledge being of such width and said engaging edge contacting said horizontal ledge from such an angle as to retain securely said cover in the clamped position, and prevent said cover from being removed without permanent deformation of a member.

3. In combination, a cylindrical container member and a circular cover member adapted to clamp on the open end of said container member, one of said members having a substantially continuous circumferential resilient rim having an engaging edge and the other member having a circumferential bead formed by an open curl providing an engaging edge, the provision and arrangement being such that when said cover member is moved toward the clamped position, said bead passes and resiliently strains said rim in passing, and when actually in the clamped position said bead is located beyond said rim, whereupon said rim returns to its normal unstrained condition, said ledge being of such width and said edge contacting said ledge from such an angle that said edge rests positively upon said ledge in such a manner that said cover member cannot

be withdrawn from the clamped position without permanently deforming at least one of said members, thereby securely retaining said cover in said clamped position.

4. In combination, a cylindrical container having a substantially continuous circumferential resilient rim formed by an open curl providing an engaging edge at its open end, and a cover adapted to be clamped to said open end, said cover having a circumferential bead provided with an engaging ledge, the normal diameters of said bead and said rim being somewhat different and such that said rim obstructs the passage of said bead, whereby when said cover is being moved toward the clamped position, said bead moves past said rim and resiliently strains said rim in passing, said bead when in the clamped position being located behind said rim and being securely held beyond said rim which then reverts to the normal unstrained condition, said ledge being of such width and said edge contacting said ledge from such an angle that said edge rests positively upon said ledge in such a manner that said cover cannot be withdrawn from the clamped position without permanently deforming said rim, thereby securely retaining the cover in the clamped position.

5. In combination, a cylindrical container having a circumferential resilient rim formed by an open curl providing an engaging edge, within the open end thereof, and a cover adapted to be clamped upon said open end, said cover having an outer circumferential bead and a circumferential resilient flange above said bead, the diameter of said bead being somewhat greater than the normal diameter of said rim, whereby when said cover is being moved toward the clamped position, said bead moves past said rim, and resiliently strains said rim to the diameter of said bead, but upon reaching the clamped position, said bead assumes a position beyond said rim, said rim then returning to its normal unstrained condition, said flange then engaging with the open end of said container and said edge engaging with said bead at a wide angle, whereby said cover is securely clamped by the resilient engagement of said rim between said bead and said resilient flange.

6. In combination, a cylindrical container having the open end thereof curled over within the top of said container to form a resilient rim having an engaging edge, and a cover adapted to be clamped upon said open end, said cover having formed thereon a protruding circumferential bead and a protruding resilient flange of greater diameter than said bead, the diameter of said bead being slightly greater than the normal inside diameter of said rim, whereby when said cover is being moved toward the clamped position, said bead moves past said rim and resiliently increases the diameter of said rim to that of said bead, but upon reaching the clamped position, said bead assumes a position beyond said rim such that said rim reverts to its normal unstrained condition and said flange resiliently engages with the open end of said container, whereby said cover is securely clamped by the engagement of the engaging edge of said rim with said bead and of said resilient flange with said open end.

7. In combination, a container member and a cover member adapted to clamp on the open end of said container member, one of said members being provided with a flange and with a bead having a substantially horizontal ledge and the other of said members being provided with a

substantially continuous resilient rim formed by an open curl providing an engaging edge, the provision and arrangement being such that when said cover member is moved toward the clamped position, said bead engages and resiliently strains said rim, and when finally in the clamped position said bead assumes a position beyond said rim and said flange presses against a corresponding surface of said rim, whereupon said rim reverts to its normal unstrained condition in such a manner that said engaging edge rests tightly on said ledge, thereby securely retaining said cover in the clamped position by reason of the tight engagement of said rim between said bead and said flange, the width of said ledge being sufficient, and the angle which said engaging edge makes with said horizontal ledge being sufficient, to prevent said cover member from being removed from the clamped position without permanent deformation of a member.

8. In combination, a cylindrical container and a cover therefor, said container having a substantially continuous resilient rim near its open edge and said cover having a circular bead for engaging said rim and also a resilient flange formed by a circumferential curl for engaging said edge, said rim and said bead being located with respect to each other so that when said cover moves toward the clamped position said bead moves past said rim and resiliently strains said rim in passing, and when in the clamped position, said bead is beyond said rim and in engagement therewith and said flange is in resilient engagement with said edge, whereby said rim re-

verts to its normal unstrained condition and said cover is securely clamped by the engagement of said bead with said rim and of said resilient flange with said edge, said bead having a ledge of such width, and the edge of said rim contacting said ledge from such an angle, that said cover cannot be withdrawn from the clamped position without permanently deforming said rim.

9. In combination, a cylindrical container having the open end thereof curled over within the top of said container to form an open curl providing a substantially continuous engaging edge, and a cover adapted to be clamped to said open end, said cover having a circumferential bead protruding from the outer circumference thereof, said bead having an engaging ledge, the normal outside diameter of said bead being greater than the normal inside diameter of said rim, whereby when said cover is being moved toward the clamped position said bead moves past said rim and resiliently strains said rim in passing, said bead when in the clamped position being located beyond said rim which then reverts to the normal unstrained condition, in such a manner that said engaging edge positively engages said engaging ledge, the outer diameter of said ledge being sufficiently greater than the normal diameter of said engaging edge, and said ledge making such an angle with respect to said edge, that said cover cannot be removed without permanently deforming said rim, thereby securely retaining said cover in the clamped position.
